Patented Nov. 8, 1921.

FIG. 1.

FIG. 2.

FIG. 3.

INVENTOR

JOHN MURRAY
BY *Harron and Harron* ATTORNEYS

UNITED STATES PATENT OFFICE.

JOHN MURRAY, OF LONDON, ENGLAND.

TYPOGRAPHIC PRINTING-PLATE.

1,396,653.

Specification of Letters Patent. Patented Nov. 8, 1921.

Application filed August 15, 1921. Serial No. 492,488.

To all whom it may concern:

Be it known that I, JOHN MURRAY, a subject of the King of Great Britain and Ireland, and a resident of London, England, 5 engineer, have invented certain new and useful Typographic Printing-Plates, (for which I have filed application in England application No. 12692, dated May 7, 1920,) of which the following is the specification.

10 In the preparation of printing surfaces for rotary machines the plates are usually cast in curved casting boxes and bored out to fit the surface of the cylinder, or they are machined to size while flat, and are then 15 bent to the desired curvature.

The degree of accuracy attained by either method is insufficient for good work and the correction of the defects entails much loss of time.

20 The invention has for its object to provide a form of plate and adapt the cylinder to receive it in such wise that the disabilities of existing methods are largely or wholly obviated.

25 According to the invention the plate, the printing surface of which may be formed in any desired manner, is initially curved as regards its outer surface to the radius of the printing surface of the cylinder upon 30 which it is mounted while its inner surface is flat or substantially so, that is to say, is chordal to the arc subtended by the outer surface. Upon the inner surface of the plate is cut a series of grooves the bottoms of 35 which are coaxial with the curvature of the outer surface. The grooves are of such depth and width as while removing surplus metal, to leave the plate of adequate strength, the upstanding portions between the grooves 40 acting as buttress webs and materially assisting to this end.

In the surface of the printing cylinder circumferential grooves counterpart to the up-standing plate are formed. Thus the co- 45 acting grooves and projections or ribs on plate and cylinder, form definite and exact locating means in a longitudinal direction, while accuracy of radial position, depending as it does upon the accuracy readily attainable in cylindrical surfaces, is assured.

The plates are secured upon the cylinder by usual or any convenient means. For ex-

ample, buttress strips having undercut edges under which the beveled edges of the plates engage and which are lodged in transverse 55 grooves in the cylinder may be provided.

An example of the carrying out of the invention is shown on an accompanying sheet of explanatory drawings in which Figure 1, is a sectional end elevation of the 60 improved plate and part of a cylinder, Fig. 2 a plan and Fig. 3 a transverse section thereof.

As shown in the drawings, the improved plate, the printing surface of which may be 65 formed in any desired manner, is initially curved as regards its outer surface A to the radius of the printing surface of the cylinder B upon which it is mounted, while its inner surface C is flat. Upon the inner surface 70 of the plate is cut a series of grooves, the bottoms D of which are coaxial with the curvature of the outer surface A and of equal radius to that of the surface of the cylinder B. The grooves are of such depth 75 and width as to lighten the plate very considerably, but at the same time leave in the webs between the grooves adequate material for strength and stiffness of the plate.

In the surface of the cylinder B are 80 formed circumferential grooves E counter-part to the ribs left projecting beneath the plate. These coacting parts on cylinder and plate form definite and exact longitudinal locating means and accuracy of radial position- 85 ing depending as it does upon the accuracy readily attainable in cylindrical surfaces, is also assured.

What I claim is:-

A typographic printing plate and cylinder 90 therefor, the plate being curved on its outer surface to the radius of the printing surface and initially flat or substantially so on its inner surface and having in its inner surface a series of grooves the bottoms of 95 which are curved to the radius of the surface of the cylinder and the cylinder having in it a series of circumferential grooves counter-part to the ribs in the inner surface of the plate, as set forth. 100

In testimony whereof I have signed my name to this specification.

JOHN MURRAY.
